UNITED STATES PATENT OFFICE.

HARRY J. POWERS, JR., OF CHICAGO, ILLINOIS.

EMERGENCY RUBBER OVERSHOE.

Application filed June 8, 1923. Serial No. 644,074.

This invention relates to a novel form of overshoee and has for its essential objects the provision of a very effective emergency rubber overshoee, adapted to be uniformly 5 rolled up into a very small space and which may be so cheaply manufactured and sold as to invite the purchase and wearing of a pair on a single occasion, but which shall, at the same time, be sufficiently durable to be 10 worn on numerous occasions if desired.

A further and important object is to so construct such an overshoee that when rolled into its compact space, it is ready for most immediate and easy application to the shoe 15 and may be correspondingly easily removed by a rolling movement, bringing it again to the small compact form ready for subsequent wear.

A further object is to make the overshoee 20 of very light construction using a very small amount of resilient material, thereby accomplishing economy and in addition causing the overshoee, by reason of its thinness and resiliency, to fit neatly in any position. To 25 this end, I make the overshoee of substantially uniform thickness throughout, whereby it may be rolled on and will invariably position itself to neatly fit the shoe, and no regard need be given to the idea of rights 30 or lefts, or even to the thought of which is top or bottom. Further advantageous and unique characteristics of my overshoee will appear in the following description, which relates to the accompanying drawings. The 35 essential characteristics are summarized in the claims.

In the drawings, Fig. 1 is substantially a side elevation of a preferred form of my overshoee, shown in position on a shoe; Fig. 40 2 is a similar view showing the overshoee partly rolled on, this same position of the material thereof, occurring on the rolling off movement; Fig. 3 is a perspective view illustrating the placing of a pair of such overshoees in a very small container when rolled; Fig. 4 is a side elevation of the overshoee before rolling; Fig. 5 is a transverse section through the same.

A lady's shoe is shown at A, with the 45 overshoee 1 in position thereon. This consists of an elongated cap or tube-like member tapered approximately as shown, and closed at one end and open at the other. At the open end is shown a slightly enlarged 50 thickened portion in the nature of a bead

with which the wall is integral, extending therefrom in a gradual taper, curving inwardly more sharply and merging with a substantially hemispherical closure at the end, as indicated at 3. Noting the cross 60 section of Fig. 5, it will be seen that the wall is of uniform thickness throughout. The bead 2 is illustrative of any suitable reinforcing means. Two or more such beads 65 may be used if desired, or for example, a broad, thicker band may serve equally well.

The material of the wall and bead is very 70 resiliant and in practice preferably not over, say, twenty or thirty thousandths of an inch in thickness, whereby great economy of material is effected. By using resilient rubber I 75 correspondingly increase the wearing quality, and practice has demonstrated that even with this thinness, a pair of these rubber overshoes may be worn on city pavements while walking many miles without showing wear.

It will be noted that the length of the tube forming the overshoee is such as to come well up into the instep, preferably 80 slightly more than half the length of the foot, so that the dampness of the pavement, shallow pools and the like, will not reach the leather of the shoe.

When the overshoes are rolled up as indicated at Fig. 3, they take the form of a rolled ring with the portion 3 across the center thereof, and may be nested very neatly in a small package or box, such, for example, as indicated at 5. From this position they 90 may be placed upon the shoes with great facility as follows:—

The ring is placed over the toe with the dome shaped portion 3 fitting over the convexity of the toe, and by a rolling motion 95 between the thumb and finger, drawing rearwardly on the shoe, the rubber wall of the shoe is drawn tightly and evenly into position, until the bead 2 comes to the position shown in Fig. 1, the operation requiring but 100 a brief moment. Because of the uniformity of the circumference of the overshoee, no attention need be paid to the thought of upper or lower portion, or of what part comes up on the sole. In fact, upon repeated wearings, the wearer may place the slightly worn portion on the upper part of the shoe, presenting a fresh surface on the sole, thus 105 accomplishing increased wear, without the necessity of thickened rubber portions as is 110

essential with previous overshoe constructions.

The removal is equally easy. The slight bead portion 2 facilitates the starting of the 5 rolling action, the application of the thumb and finger to opposite sides of the shoe with a forward movement, causing a uniform rolling action, rolling the wall around the bead more or less loosely, as illustrated in 10 Fig. 2. The complete removal is effected by continuation of this movement, and results in the overshoe again taking the form shown in Fig. 3, ready for the next convenient application, as described.

15 From the foregoing description it will be seen that I have provided an overshoe adapted to take a very compact form, which may be very cheaply manufactured, both by reason of its extreme simplicity and the 20 small amount of material required. The resiliency adds to the wearing quality and causes it to adjust itself to any shape of shoe. A minimum number of sizes will suffice for a wide variety of sizes of shoes, be- 25 cause of the resiliency and stretch of which the overshoes are capable.

The circumferential uniformity of the

wall of the tube forming the overshoe results in great facility in placing the overshoe in position to be worn, there being no seams or sole portions which must be accurately placed in position, and which result in the necessity of having rights and lefts.

When in position my overshoe presents a very neat and trim appearance, being in 30 fact, quite unnoticeable and yet very effectively accomplishing the purpose of keeping the foot dry.

Having thus described my invention, what I claim is:—

40 An overshoe of the character described consisting of a tube of resilient nature, having one end closed in a convex portion integral with the wall of the tube, the tube being normally annular, and substantially uniform at any plane of transverse cross section, and having a reinforced portion at its open end, and being of a length corresponding to substantially half of the shoe for which it is intended.

45 In testimony whereof, I hereunto affix my signature.

50 HARRY J. POWERS, JR.
